CLAIM

The ornamental design for a drinking fountain bubbler, as shown and described.

DESCRIPTION

FIG. 1 is a perspective view taken from the top, front and right side of a drinking fountain bubbler showing my new design;

FIG. 2 is a rear elevational view thereof;

FIG. 3 is a right side elevational view thereof, the left side being a mirror image of the right side shown;

FIG. 4 is a top plan view thereof; and

FIG. 5 is a bottom plan view thereof.
